UNITED STATES PATENT OFFICE.

JOHN DI CIO, OF NORRISTOWN, PENNSYLVANIA.

WOMEN'S AND MISSES' UNDERWEAR.

Application filed January 22, 1927. Serial No. 162,777.

This invention relates to apparel, particularly to combination garments, and has for its general object the provision of a combined upper and nether garment, the former being similar to the upper portion of a slip and taking the place of a shirt or chemise and the latter being of such construction as to constitute bloomers.

The object of the invention, more specifically stated, is to provide a combination garment having a novel reinforcing means suitably secured and located at the front and back so as to increase the durability and not only reduce wear but give sufficient additional strength to prevent wearing in case of sudden strain.

An important object of the invention is to provide a garment of this character so constructed and arranged as to open at the back of the waistline, elastic being provided along the line of closure for the purpose of permitting yieldability to accommodate bending movements of the wearer while normally maintaining the garment in snug engagement about the body so that undesired looseness and gathering or bunching at any localized point or points will be prevented.

A still more specific object is to provide a garment of this type in which the reinforcement at the seat portion constitutes pieces or plies secured upon the outside and the inside, the main fabric being cut away at the area covered by the reinforcing plies.

Yet another object is to provide a garment in which the reinforcement for the crotch and the seat are united to each other and to the main fabric along the same line or lines, the number of lines of stitching needed and cost of manufacture being consequently reduced, the lines of union of the reinforcements being coincident with the inseam which unites the front and back breadths.

A further object is to provide a garment of this character which embodies very few sections or parts which may be cut economically from goods on the wholesale plan, if desired, and which may be quickly and easily stitched together.

An additional object is to provide a combination garment which will be simple and

inexpensive to manufacture, neat and attractive in appearance, durable in service, comfortable and convenient in use, and a general improvement in the art.

With the above and other objects and advantages in view, the invention preferably consists in the arrangement and combination of parts and detailed structural features to be hereinafter more fully described and claimed, and illustrated in the accompanying drawing in which:

Figure 1 is a front elevation of the garment.

Figure 2 is a rear elevation thereof,

Figure 3 is a detail sectional view taken through a portion of the seat showing the construction of the reinforcement, the view being taken on the line 3-3 of Figure 2,

Figure 4 is a similar detail section taken through the reinforcement at the front.

Referring more particularly to the drawing I have shown the garment as conforming, generally, to well accepted standards in so far as style is concerned, at least as regards the upper portion which resembles the upper portion of a slip, teddy or the like. It is preferable that the front 10 be formed from a single piece and the front includes a torso or body engaging portion 11 and leg portions 12. The garment also includes an upper back portion 13 which is joined at its side edges to the sides of the front top portion 11 as by lines of stitching 14. The top is shown as provided with a hem 15 within which is the usual ribbon, tape or the like 16 which may be drawn to bring the garment into proper engagement with the body and tied, as is the usual practice. The top is also equipped with shoulder straps 17 as is ordinarily the case. The line of stitching 14 terminates at a point spaced from the lower edge of the back member 13 to provide a loose flap 18 which slightly overlaps the side edges of the front 10.

The garment further includes a lower back portion indicated as a whole by the numeral 19 and this member is formed with or includes leg portions 20 secured at their edges to the side edges of the front leg portions 12 as by lines of stitching 21. The

inner edges of the leg portions 12 and 20 are secured together by lines of stitching 22.

A very important feature of the invention is the provision of reinforcing means 5 at the crotch and at the seat. The first mentioned reinforcing means is shown as comprising a crescent shaped piece or ply of fabric 23 located at the lower portion of the front member 10 with its concave 10 edge registering with the concave lower edge of the member 10. This reinforcement is secured to the front member 10 by a curved line of stitching 24. The reinforcement at the seat comprises outer and inner 15 pieces or plies 25 and 26 located respectively against the outside and inside of the lower back member 19 and of course extending to the lower edge of the front member 10 and reinforcement 23 therefor. The front 20 and back reinforcements are secured together by lines of stitching 27, the seam being a continuation of that formed by the lines of stitching 22 which define the inseams. The reinforcing members 25 and 26 25 are secured to each other and to the lower back portion 19 by curved lines of stitching 28. It is of course conceivable that the fabric of the lower back portion 19 may be left intact at the area covered by the seat 30 reinforcement but in the present instance I have shown the seat portion as cut away or formed with an opening 29 within the confines of the pieces 25 and 26 so that no strains will come upon the major portion 35 of the goods within this area, any pulling strains resulting, for instance, from sudden body movements being communicated to the seams formed by the lines of stitching 27 and 28. As these seams consist of several 40 thicknesses it is clear that they will have considerable strength and be able to withstand any and all normal strains to which the garment may be subjected in use.

The ends of the legs are suitably hemmed 45 at 30 and provided with elastic so that the legs will fit snugly upon the wearer as is customary in bloomer construction. For holding the garment closed at the back, some suitable fastening means must be provided 50 and in the present instance I have shown this as including buttons 31 on the upper back portion 13 engageable by button holes 32 in the upper corners of the lower back member 19. The upper edge of the lower back member 19 is suitably hemmed at 55 33 and inserted therein is an elastic strip 34 which need not extend entirely to the sides of the member 19 but which preferably terminates a distance of several inches from 60 the button holes. The purpose of this elastic is to hold the garment snugly about the waist of the wearer while permitting it to yield in accordance with body movements so that undue strain upon the buttons and 65 button holes, or other securing elements, and

upon the garment itself will be avoided. The flap 18 extends down below the upper edge of the lower back member 19 so that a certain degree of relative movement of the upper and lower back members 13 and 19 70 may occur without actual separation.

In the actual making of the garment, it is conceivable that the fabric may be folded and cut, or cut without folding, in such manner that the piece resulting from cutting out the portion 29 may be used as the front reinforcement 23. It is also conceivable that after the portion 29 is cut out this same piece might be used to constitute one of the seat reinforcements 25 or 26, it being of course necessary in such an event that the leg portions be moved slightly closer together so as to provide an overlap at the edges of the piece thus used as a seat reinforcement and the edges at the cut away 80 portion 29. As a matter of fact this latter mentioned alternative plan would not be followed. Incidentally, it is believed immaterial how the fabric is cut provided of course that the desired result is obtained. The garment is put on or taken off in an obvious manner and no explanation in regard thereto should be necessary.

From the foregoing description and a study of the drawing it will be apparent that I have thus provided a simply constructed, inexpensive, neat and attractive and highly satisfactory garment which will take the place of the two garments ordinarily required. The device has the advantage of being all in one so that the upper and nether garments are always in association. The provision of the elastic at the top of the lower back member holds the garment properly in place without any objectionable pressure upon or constriction about the waist inasmuch as the elastic extends only across the flat portion or small of the back. It is really believed that the construction and advantages will be readily apparent to one skilled in the art without further elaboration.

While I have shown and described the preferred embodiment of the invention it should be understood that the disclosure is simply an exemplification of the general principles involved together with a specific means for carrying them out and the right is reserved to make all such changes in the details of construction and arrangement as will not depart from the spirit of the invention or the scope of the subjoined claim.

Having thus described the invention, I claim:

In a combination garment, a front member terminating at its lower end in leg portions, a back including an upper portion and a separate lower portion, the latter terminating in leg portions, the side edges of both back portions being secured to the side 120 125 130

edges of the front portion, the upper edge of the lower back portion and the lower edge of the upper back portion being free from the front portion and overlapping each other at the waistline, means for detachably connecting the top of the lower back portion with the upper back portion, an elastic strip within the upper edge of the lower back portion for holding the garment snugly

about the waist, the upper edge of the lower back portion having a hem within which said elastic strip is enclosed, and said strip terminating at considerable distances inwardly from the upper corners of said lower back portion.

In testimony whereof I affix my signature.

JOHN DI CIO.
